UNITED STATES PATENT OFFICE.

CHARLES C. BLAKE, OF BROOKLINE, MASSACHUSETTS, ASSIGNOR TO C. C. BLAKE,
INCORPORATED, OF BOSTON, MASSACHUSETTS, A CORPORATION OF NEW
YORK.

WORK-SUPPORT.

1,314,385.

Specification of Letters Patent. Patented Aug. 26, 1919.

Application filed November 4, 1915. Serial No. 59,654.

To all whom it may concern:

Be it known that I, CHARLES C. BLAKE, a citizen of the United States, residing at Brookline, in the county of Norfolk and 5 State of Massachusetts, have invented a new and useful Improvement in Work-Supports, of which the following is a specification.

The present invention relates to work supports, and more particularly to work supports for use in automatic shoe machines.

In the automatic shoe machines which are used in the manufacture of the welt shoe devised by me the work is carried upon a leader which is fed longitudinally to transfer the point of operation of the tool around the work and which is automatically shifted laterally during its feed longitudinally to maintain the edge of the work adjacent the operating tool in the line of feed. It is 20 highly desirable that the same leader used in the earliest shoe bottoming operation on one shoe should be used in the subsequent shoe bottoming operations on the same shoe. As some of these machines operate before 25 and others after the application of the toe-box to the toe end of the insole heretofore it has been considered impracticable to employ the same leader in the various automatic shoe bottoming machines. The chief 30 difficulty encountered is that a leader constructed for use in a shoe bottoming operation prior to the application of the toe-box to the toe end of the insole will cause the outsole to encroach on the inseam in the 35 outsole stitching operation.

The object of the present invention is to provide means whereby the same leader may be used in the automatic machines for performing operations both prior and subsequent to the application of the toe-box to the toe end of the insole.

To the accomplishment of this object, and such others as may hereinafter appear, the features of the invention relate to certain 45 devices, combinations and arrangements of parts hereinafter described and then set forth broadly and in detail in the appended claims, which possess advantages readily apparent to those skilled in the art.

50 The various features of the present invention will be best understood from an inspection of the accompanying drawings

illustrating the best form of the invention at present known to the inventor, in which,

Figure 1 is an elevation, partly in section, of the work mounted in position upon a leader;

Fig. 2 is a diagrammatic plan illustrating the relation between the edge of the last bottom and the guiding flange on the leader; 60

Fig. 3 is a plan of the jack mounted upon the leader.

In the illustrated embodiment of the invention the lasted shoe, hereinafter called 65 for convenience the "shoe," is mounted on a jack 1 which is carried by a leader 2. The leader 2 is provided with a depending flange 3 the outside face of which is provided with rack teeth 4 for engagement with 70 a driving pinion of an automatic machine. The lasted shoe comprises a last 5 (Fig. 2) upon the bottom of which an insole 6 is secured. To the edge face of the insole 6 an upper 7, having the toe-box within it, is 75 lasted in accordance with the method described in the application for Letters Patent of the United States filed by me April 14, 1915, Serial No. 21,423.

In order that the leader may properly 80 guide the shoe or the parts therefor for the operation of the operating tool or tools in the automatic machine the inside face of the guiding flange, indicated at 8 (Figs. 1 and 2) has a definite relation to the edge of 85 the lasted shoe. When the last and insole are first positioned on the leader the projections of the edge of the last or insole at the sides thereof upon the plane of the leader coincide with the face 8. At the toe of the 90 last or insole the projections of the edge of the last or insole upon the plane of the leader fall within the guiding flange. This variation is for the accommodation of the toe-box which is applied to the toe end of 95 the insole during the lasting operation. When the upper 7, having the toe-box within it, is lasted to the edge face of the insole, in accordance with the method of lasting practised by me, the projections of the edge 100 of the upper adjacent the edge face of the insole upon the plane of the leader, will coincide with the inside face 8 of the guiding flange throughout its length. Stated in

another way, the projections upon the plane of the leader of the outside edge of the toe-box secured in position against the toe end of the insole will coincide with the face 8 of 5 the guiding flange at the toe of the leader.

The shoe is mounted on a spindle 9 and a saddle 10. The spindle 9 is secured to a boss 11 (Fig. 3) formed in a plate 12 carried by two vertical plates 13 rising from a base 10 14. The saddle 10 consists of a pad of yielding material mounted upon the upper end of a chambered post 15. The post 15 is mounted upon a standard 16 and is guided to slide vertically therein by a 15 screw 17 which is arranged to engage a slot 18 formed in the post 15. The saddle 10 is normally held elevated by a coiled spring 19 which is interposed between the bottom of the standard 16 and the top chamber in 20 the post 15. To permit the saddle to be forced upwardly to jack the shoe the post 15 carries a rack 20 which, when the saddle is under the influence of the spring 19, registers with an opening 21 formed in a 25 worm 22. This worm is mounted in a housing 23 on a vertical shaft 24 journaled in the standard 16, and is provided with a handle 25 by means of which the operative may engage the worm with the rack 20 and force 30 the saddle 10 upwardly to jack the shoe. To permit the jack to accommodate different sizes of shoes the standard 16 is mounted to slide in ways 26 formed on the plates 13. The base 14 is provided with a frame 27 35 (Fig. 3) projecting laterally on both sides thereof. The frame 27 is provided with a pair of runners 28 which extend downwardly to the plane of the bottom of the guiding flange 3.

40 In order to permit the last 5 to be originally positioned properly with relation to the leader 2 the leader is provided with a pair of button-hole slots (Fig. 1) which receive headed bolts 30 carried by the base 45 14 of the jack. With this construction the jack may be placed upon the leader by passing the heads of the bolts 30 through the large ends of the button-hole slots 29. The jack is then shifted on the leader until the 50 last is centrally located with relation to the guiding flange on the leader. This movement of the jack brings the shanks of the bolts within the small ends of the button-hole slots 29. To clamp the jack to the leader the ends of the shanks of the bolts are provided with pins 31 which are engaged by the opposite ends of a leaf spring 32 arranged to embrace the shanks of the bolts. The spring is bowed to exert clamping 55 pressure upon the bolts and thus clamp the jack to the leader by a triangular cam 33 secured to a shaft 34 journaled in the plates 13 and actuated through a handle 35 (Fig. 60 3) carried by the shaft. The base 14 carries 65 a pair of pins 36 which act as fulcrums

for the leaf spring 32 during the bowing thereof.

The leader 2 is also provided with a cam face 37 (Fig. 1). When the leader is used in the automatic shoe machines which perform operations on the work before the application of the toe-box thereto this cam face 37 operates to shift the tool transversely of the feed to accommodate for the toe-box variation in the guiding flange of the leader. 70 In the automatic shoe machines which perform operations subsequent to the application of the toe-box to the shoe the cam face 37 has no function. Consequently the guiding flange operates to transfer the point of 75 operation of the tool at a uniform distance from the outside edge of the toe-box in passing around the toe of the shoe. Therefore this construction provides for the maintenance of a predetermined distance 80 between the inseam and the outseam around the toe of the shoe a result heretofore considered impracticable. 85

It will be clear to those skilled in this art, and with the general objects of the present 90 invention in view, that changes may be made in the details of structure, the described and illustrated embodiment thereof being intended as an exploitation of its underlying 95 essentials, the features whereof are definitely stated in their true scope in the claims here-with.

What is claimed as new, is:—

1. A work support, having, in combination, a support for a last, and a leader connected to the support provided with a guiding flange which is so arranged relatively to the last on the support that the projections of the edge of the last at the sides thereof upon the plane of the leader coincide 100 with the guiding flange and the projections of the edge of the last at the toe thereof upon the plane of the leader fall within the guiding flange, substantially as described. 105

2. A work support, having, in combination, a support for a lasted shoe, and a leader connected to the support provided with a guiding flange which is so arranged relatively to the lasted shoe on the support that the projections of the edge of the upper 110 adjacent the edge face of the insole upon the plane of the leader coincide with the guiding flange, substantially as described. 115

3. A work support, having, in combination, a support for a lasted shoe, and a leader connected to the support provided with a guiding flange which is so arranged relatively to the support for the lasted shoe that the projections of the outside edge of the toe-box positioned against the toe end of the 120 insole coincide with the guiding flange of the leader at the toe thereof, substantially as described. 125

4. A work support, having, in combination, a sole support, and a leader connected 130

to the support provided with a guiding flange which is so arranged relatively to the sole on the support that the projections of the edge of the sole at the sides thereof upon the plane of the leader coincide with the guiding flange and the projections of the edge of the sole at the toe thereof upon the plane of the leader fall within the guid-

ing flange, the area between the guiding flange and the line through the projections 10 inside the guiding flange equaling the cross sectional area in the plane of the sole of a toe box positioned against the toe end of the sole on the support.

CHARLES C. BLAKE.
